UNITED STATES PATENT OFFICE.

GEORGE P. WIGGINTON, OF KALAMAZOO, MICHIGAN, ASSIGNOR TO OFFICE EQUIPMENT PATENT CORPORATION, OF NEW YORK, N. Y., A CORPORATION OF NEW YORK.

SHEET OR CARD HOLDER.

Application filed May 9, 1927. Serial No. 189,969.

My present improvements relates to the type of visible card index or holder shown in my application for Letters Patent No. 151,093, filed November 27, 1926, the same being an adaptation and in some respects an improvement upon the structure there disclosed.

The main object of this invention is to provide an apparatus of the class described in which the sheet or card holders are supported so that they may be adjusted and retained in adjusted positions on the support and relative to each other.

A further object is to provide a sheet holder which is of large capacity, that is, a large number of sheets or cards may be effectively supported and displayed, and sheets added thereto or removed therefrom as occasion may require.

Objects pertaining to details and economies of my invention will appear from the description to follow. The invention is defined in the claims.

A structure embodying the features of my invention is clearly illustrated in the accompanying drawing, in which:

Fig. 1 is a perspective view of a binder of the loose leaf type containing a plurality of sheet-like supports or units embodying the features of my invention.

Fig. 2 is a fragmentary plan view of a pair of units disposed in proper relation to permit the shifting of the sheet holders from one of the units to the other.

Fig. 2^a is a top edge view of a support with the releasing bars omitted.

Fig. 3 is an enlarged lower edge view of one of the units, the hinged binding flap thereof being omitted.

Fig. 4 is a detail section on line 4—4 of Fig. 2 showing details of the holder and the relation of the sheet-attaching members thereto.

Fig. 5 is a plan view of one of the holders, a fragment of a sheet being shown in operative relation thereto.

Fig. 6 is an enlarged detail view illustrating the manner of engaging and disengaging the sheet holders with the support.

Fig. 7 is an enlarged detail section on line 7—7 of Fig. 2, the sheet being omitted.

Fig. 8 is a fragmentary section on line 8—8 of Fig. 7 illustrating the means of re-

leasing the holders to permit their sliding adjustment on their supports. 55

Referring to the drawing, 1 represents a loose sheet binder provided with binding or clamping bars 2. As the details of the binder form no part of the invention they are not illustrated herein. 60

The binder is adapted to receive a plurality of units designated generally by the numeral 3, these units being provided with binding flaps 4. Each unit, as illustrated, carries two sets or series of sheet or card holders, one on each face. 65

In the embodiment illustrated the units comprise a plate-like body 5 having spaced pairs of bars 6 secured to the sides thereof, the inner edges of the bars being rabbeted to coact with the plate, providing spaced groove-like ways 7 facing toward each other. Between these bars 6 and in spaced relation thereto are mounted inner bars or plates 8 which are spaced to provide the forwardly facing central groove-like ways 9. One of each pair of bars 8 is provided with a series of spaced aligned holes 10. 70

The holders 11 which are formed of spring sheet material have inwardly offset ends 12 engageable with and slidable in the ways 7. These holders also have pairs of inwardly projecting lugs 13 which engage the groove 9, thereby supporting the bars against swinging movement when the lugs 85 are engaged, preventing binding and also accidental disengagement. 75

The holders are provided with inwardly projecting pins 14 engageable with the holes 10, thereby supporting the holders against 90 sliding movement when these pins are engaged. To release or disengage the pins or to permit sliding adjustment of the holders, I provide a flat releasing bar 15 which is pivoted at its ends at 16 and provided near one end with a finger piece 17 which permits the bar being swung to a vertical plane shown in Fig. 7, disengaging the pins so that the holders may be shifted in their supporting ways. 95

With the pins disengaged as shown in Fig. 7, any selected holder may be removed by springing to disengage one end and then shifting laterally, and they may be inserted by a reverse movement, or the holders may be separated and additional holders inserted. 100 105

Further, the holders may be spaced as desired, that is, when it is desired to remove a holder for any purpose, the space which it occupies is left blank as the holders are individually retained against sliding movement.

Each sheet holder is provided with a sheet-attaching member 18 which has inturned hooks 19 at its ends adapted to engage holes 20 in a card or sheet 21. The attaching member has pivots 22 engaging the knuckles 23 which are disposed centrally of the holder 11 so that the springing of the holder does not effect the attaching member and the attaching member does not prevent springing of the holder for engaging and disengaging the same, and permits its springing to disengage the pins.

The ways are preferably open at the ends 20 of the holders so that a pair of holders may be alined as shown in Fig. 2, the supports having projecting pins 24 at one end to engage coacting sockets or recesses 25 at the other end, thereby facilitating the alinement, 25 and sheets transferred from one to the other substantially as shown in my said application.

I have illustrated and described my improvements in an embodiment which I consider very satisfactory. I have not attempted to illustrate and describe certain modifications and adaptations which I contemplate as I believe this disclosure will enable those skilled in the art to embody or 35 adapt my improvements as may be desired.

Having thus described my invention what I claim as new and desire to secure by Letters Patent is:

1. In an apparatus of the class described, 40 the combination of a support having spaced groove-like ways facing toward each other, a plurality of sheet holders of resilient material having inwardly offset ends slidably engaging in said ways, said support being provided with a series of spaced holes disposed in parallel relation to said ways, pins 45 on said holders adapted to engage said holes whereby said holders are supported in adjusted positions, and a releasing bar pivotally mounted behind said holders adapted to disengage said pins to permit sliding adjustment of said holders, said holders being provided with sheet-attaching means pivotally mounted thereon.

2. In an apparatus of the class described, 55 the combination of a support having spaced groove-like ways facing toward each other, a plurality of sheet holders of resilient material having inwardly offset ends slidably engaging in said ways, said support being provided with a series of spaced holes disposed in parallel relation to said ways, and pins on said holders adapted to engage said holes whereby said holders are supported in 60 adjusted positions.

3. In an apparatus of the class described, the combination of a support having spaced ways facing toward each other and a series of spaced alined holes, a plurality of sheet holders having ends slidably engaged in said spaced ways, and pins engageable in said holes, said holders being of spring material, and a releasing member disposed behind said holders and adjustable to disengage said pins permitting sliding adjustment of said 75 holders.

4. In an apparatus of the class described, the combination of a support having spaced ways facing toward each other and an intermediate forwardly facing way and a series of 80 spaced alined holes, a plurality of resilient sheet holders having ends slidably engaged in said spaced ways and portions engaging said forwardly facing way and pins selectively engageable with said holes whereby 85 the holders are supported in their adjusted positions, and means for simultaneously disengaging said pins without disengaging the holders from said ways permitting their sliding adjustment in the ways.

5. In an apparatus of the class described, the combination of a support having spaced ways facing toward each other and a series of spaced alined holes, a plurality of resilient sheet holders having ends slidably engaged in said spaced ways and pins selectively engageable with said holes whereby 90 the holders are supported in their adjusted positions, and means for simultaneously disengaging said pins without disengaging the holders from said ways permitting their sliding adjustment in the ways.

6. In an apparatus of the class described, the combination of a support having spaced ways facing toward each other and an intermediate forwardly facing way and a series of spaced alined holes, and a plurality of resilient sheet holders having ends slidably engaged in said ways and portions engaging said forwardly facing way and pins selectively engageable with said holes whereby 105 the holders are supported in their adjusted positions.

7. In an apparatus of the class described, the combination of a support having spaced ways facing toward each other and a series of spaced alined holes, and a plurality of resilient sheet holders having ends slidably engaged in said spaced ways and pins selectively engageable with said holes whereby 110 the holders are supported in their adjusted positions.

8. In an apparatus of the class described, the combination of a support having spaced ways and an alined series of holes, a plurality of resilient sheet holders having their ends slidably engaged in said ways and provided with pins selectively engageable with said holes, a releasing bar pivotally mounted 115 below said holders and adjacent said holes 120

125

130

whereby the releasing bar may be rotated to disengage said pins, permitting the sliding adjustment of said holders, and sheet-attaching means pivotally mounted on said 5 holders centrally thereof.

9. In an apparatus of the class described, the combination of a support having spaced ways and an alined series of holes, a plurality of resilient sheet holders having their 10 ends slidably engaged in said ways and provided with pins selectively engageable with said holes, and a releasing bar pivotally mounted below said holders and adjacent said holes whereby the releasing bar may be 15 rotated to disengage said pins permitting the sliding adjustment of said holders, said holders being provided with sheet-attaching means.

10. In an apparatus of the class described, 20 the combination of a support having spaced ways and a series of alined holes, and sheet holders of resilient material having their ends engaging in said ways and provided with pins selectively engageable with said 25 holes whereby the holders are retained in their adjusted positions on the support, said holders being capable of being sprung to permit the disengagement of said pins without disengaging the holders from said ways, 30 said holders being provided with pivoted sheet-attaching members.

11. In an apparatus of the class described, 35 the combination of a support, a plurality of sheet holders removably and slidably mounted on said support, said support being provided with a series of spaced holes, said holders being provided with coacting pins

whereby the holders are individually supported against sliding movement, and means for simultaneously disengaging the pins 40 from the holes to permit sliding adjustment of the holders.

12. In an apparatus of the class described, the combination of a support, a plurality of sheet holders removably and slidably mounted on said support, said support being provided with a series of spaced holes, said 45 holders being provided with coacting pins whereby the holders are individually supported against sliding movement. 50

13. In an apparatus of the class described, the combination of a support, a plurality of holders slidably mounted on said support and provided with means for individually retaining said holders in their adjusted positions on said support, and means for simultaneously releasing said retaining means 55 to permit sliding adjustment of the several holders.

14. In an apparatus of the class described, 60 the combination of a support, and a plurality of holders slidably mounted on said support, said holders each being provided with a support-engaging member, and said support being provided with a plurality of co-engaging means with which said support-engaging members may be selectively engaged for retaining said holders in their 65 adjusted positions on said support, and permitting their sliding adjustment when said members are disengaged. 70

In witness whereof I have hereunto set my hand.

GEORGE P. WIGGINTON.
